UNITED STATES PATENT OFFICE.

ROBERT SPURGIN, OF CHICAGO, ILLINOIS.

INDEX FOR LETTER-BOOKS.

SPECIFICATION forming part of Letters Patent No. 337,454, dated March 9, 1886.

Application filed July 6, 1885. Serial No. 170,801. (No model.)

To all whom it may concern.

Be it known that I, ROBERT SPURGIN, of Chicago, in the county of Cook and State of Illinois, have invented an Improved Index 5 for Letter-Books, of which the following is a specification.

Hitherto it has been usual to make indices of this sort in what is known as the "cabinet form," in which the only clue to the desired 10 letter is the name of the writer.

My invention lies, principally, in the fact that my improved index retains the alphabetical arrangement of the names of the writers, which, as I have stated, is the chief feature of 15 letter-book indices now in common use, and presents the new and valuable feature of retaining the order of date in the index itself, whereby my index presents two varieties of information in a compact form, which have 20 never before been united in the same index, thereby affording a new clue in the search for any letter in the index—to wit: the date of the letter or the order in which the letters occur in the book.

25 In the accompanying drawing, illustrating my invention, my index is represented in its usual form, covering two pages of the book.

It will be observed that I have shown vertical columns headed by letters of the alphabet, 30 a column headed "Page," one headed "Date," and another headed "Subject." The central vertical column headed "Page" contains printed figures from 1 up, indicating pages of the book. It will be observed that each of these 35 figures stands between horizontal rulings, and that there is therefore a horizontal subdivision or section of the paper extending entirely across the two pages of the index for each page of the letter-book. As each letter is written

40 and recorded in the book I enter the name of the writer in the rectangle at the intersection of the horizontal section of the index bearing the number of the page on which the letter is recorded, and the vertical section or column headed by the first letter of the name. I enter 45 the date of the letter in the same horizontal section under the column-heading "Date," and under the heading "Subject" I enter a brief statement of the subject-matter of the 50 letter. It is evident that with an index constructed and filled up in this manner knowl-

edge of either the subject-matter, the date, or the name of the writer of any letter will suffice to enable it to be readily found.

As an additional aid in the use of the index, 55 and to facilitate search when the date or approximate date of the letters only is known, I propose to affix tabs to each leaf, or to each second or third leaf, as convenient, on the subject-column side, placing on the tab the 60 date of the horizontal section corresponding to it, as indicated in the drawing.

While I have described the figures in the column headed "Page" as printed, the spaces in that column may be left blank and the figures filled in by the book-keeper when making 65 the entries.

My index is capable of being used for letters received as well as for letters sent with little or no change. If such letters are fixed for 70 preservation to the pages of a book, the number in the column headed "Page" will indicate the page of the book on which the letter is placed.

If the letters are filed in other ways, as by 75 placing them in boxes or on wires, they may be numbered in their order, and in that case the numbers in the vertical column will indicate the number assigned to each letter, and that column should be headed "Number of 80 letter."

In cases where the letters are short and more than one is contained on a page of the letter-book, the proper number of separate entries may be made in the single line appropriated 85 to the page, and to facilitate the separation of two such entries I propose to have the index ruled with faint central lines in the horizontal sections, as shown by the dotted line *xx* of the drawing. These lines may extend entirely 90 across the face of the index, or may be confined to the column headed "Subject."

When the letter extends over several pages of the letter-book, several lines of the index will be appropriated to it and brackets used, 95 as shown in the drawing.

While I have shown twenty-five lines in the drawing upon one page, any convenient number may be so entered. Similar successive pages should be added until the number of 100 horizontal sections equals the number of pages in the letter-book.

It will be observed that several of the least common of the letters of the alphabet are grouped together in single vertical columns. Greater compactness is thus secured without materially detracting from the merit of the index. The index may, however, be printed with a separate column for each letter of the alphabet.

Modifications of construction shown which may be useful are the use of two columns to headed "Page" or "Number of letter" on the right and left hand sides of the double pages, respectively, instead of at the fold of the double pages, as shown, and which might render the indexing and reference a little more convenient, the addition of a column adjoining the subject-column, for containing reference to other letters on the same subject or for noting dates of answers, the reduction of the proportionate width of the alphabet-columns, and a corresponding increase of the width of the subject-column.

What I claim, and desire to secure by Letters Patent, is—

1. A letter-book index having vertical columns headed by letters of the alphabet and horizontal sections numbered consecutively from 1 up, the said numbers indicating the page of the book upon which the letters indexed in the horizontal sections are to be found, substantially as described and shown. 25
2. A letter-book index having vertical columns headed by letters of the alphabet, horizontal sections numbered consecutively, and provided also with a vertical column for recording dates in consecutive order, substantially as described and shown. 30 35

ROBERT SPURGIN.
